UNITED STATES PATENT OFFICE

LESTER M. SAWIN, OF CHICAGO, ILLINOIS, ASSIGNOR TO GENERAL NUT COMPANY, OF CHICAGO, ILLINOIS, A CORPORATION OF ILLINOIS

DESIGN FOR A BOX FOR NUTS, CONFECTIONERY, AND THE LIKE

Application filed June 23, 1930. Serial No. 36,148. Term of patent 14 years.

To all whom it may concern:

Be it known that I, LESTER M. SAWIN, a citizen of the United States, residing at Chicago, in the county of Cook and State of Illinois, have invented a new, original, and ornamental Design for a Box for Nuts, Confectionery, and the like, of which the following is a specification, reference being had to the accompanying drawing, forming part hereof, in which—

for nuts, confectionery and the like, showing my new design. The drawing is lined for color.

Fig. 2 is an elevation of the edge of the box which is not visible in Fig. 1.

I claim:

The ornamental design for a box for nuts, confectionery and the like, as shown and described.

LESTER M. SAWIN.
